UNITED STATES PATENT OFFICE.

ALBERT EDMUND HUDSON, OF TORONTO, ONTARIO, CANADA, ASSIGNOR OF ONE-THIRD TO HENRY BUSH SPENCER AND ONE-THIRD TO ROBERT HUDSON, BOTH OF OTTAWA, ONTARIO, CANADA.

SPARK-ARRESTER.

1,223,388.

Specification of Letters Patent.

Patented Apr. 24, 1917.

Application filed July 18, 1916. Serial No. 109,917.

To all whom it may concern:

Be it known that I, ALBERT EDMUND HUDSON, a subject of the King of Great Britain, and resident of the city of Toronto, Province 5 of Ontario, Dominion of Canada, have invented certain new and useful Improvements in Spark-Arresters, of which the following is the specification.

This invention relates to improvements 10 in spark arresters particularly adapted for use in locomotives and the like, and the objects of the invention are to facilitate in assembling the arrester and operatively mounting the same on a locomotive, to render the 15 arrester easily accessible for inspection or repair, to simplify the construction and generally to adapt the several parts to better perform the functions required of them.

With the above and other objects in view 20 the invention consists essentially of the improved construction particularly described and set forth in the following specification and accompanying drawings forming part of the same.

25 In the drawings,

Figure 1 is a longitudinal sectional elevation of a boiler embodying the present invention.

Fig. 2 is a transverse section of the same.

30 Fig. 3 is a fragmentary longitudinal sectional plan view of a boiler embodying the present invention.

Fig. 4 is a transverse section through a pair of baffle plates.

35 Fig. 5 is a fragmentary front elevation of one of the baffle plates showing the means for supporting the same.

Like characters of reference refer to like parts in the several figures.

40 Referring to the drawings, A represents a locomotive boiler of usual construction having a smoke stack 11 mounted on the top of the smoke box 10 which carries a baffle wall 12 extending transversely across the front of the tube plate 13 and provided at the upper edge with an offset portion 14 located adjacent to the smoke stack.

45 This baffle plate extends downwardly for about two-thirds of the diameter of the smoke box, when it is offset outwardly in a substantially V-shaped portion 15 provided with a downwardly extending flange 16, the portion 15 being provided with an orifice 17 therethrough, with which the upper end 50 of the conduit 18 engages.

That part of the smoke box immediately in front of the smoke stack 11 is inclosed by a wall 19 of wire netting, the lower end of which engages with the flange 16 while the edges of the said wall snugly engage 60 with the inner periphery of the smoke box.

A pair of offset straps 20 are rigidly secured to the smoke box 10 adjacent to the baffle wall 19 and the flange 16, and carry a plurality of longitudinally extending bars 65 21 operatively supporting a plurality of transversely extending and angularly disposed bars 22 on which the baffle plates 23 are rigidly mounted.

These baffle plates are made of wire netting and the adjacent rows of the said baffle plates are angularly disposed in opposite direction and staggered relatively to each other.

The assembly of the spark arrester will be 75 readily understood from the foregoing description.

When a boiler fitted with a spark arrester of this description is in use the products of combustion from the fire box are delivered 80 through the tubes into the smoke box 10 and passing beneath the offset portion 15 of the plate 12 pass up through between the baffle plates 23 and thence through the baffle wall 85 of wire netting 19 and are delivered to the smoke stack 11.

During the passage of the products of combustion through the smoke box 10 the cinders are deflected backwardly and forwardly as often as possibly by the baffle 90 plates 23 so that when the cinders are finally delivered to the smoke stack 11 they will be extinguished.

Should any of the cinders remain glowing after passing the baffle plates 23 they will on 95 impact with the perforated wall 19 be again deflected and extinguished before they reach the smoke stack.

From this description it will be seen that I have invented a spark arrester simple of 100 construction and capable of being readily mounted in the smoke box of a boiler, the several parts being easily accessible in case of repair or inspection.

As many changes could be made in the 105 above construction and many apparently widely different embodiments of my invention, within the scope of the claim, constructed, without departing from the spirit or scope thereof, it is intended that all mat- 110

ter contained in the accompanying specification and drawings shall be interpreted as illustrative and not in a limiting sense.

What I claim as my invention is:

5 The combination with a boiler, of a spark arrester consisting of a baffle wall extending transversely across the upper portion of the smoke box of the boiler and provided with a lower offset portion of substantially V-
10 shape, having a flange therearound, a curved perforated baffle wall located in front of the said baffle wall and coacting therewith, a pair of vertically disposed

straps adjacent baffle wall, a plurality of 15 pairs of longitudinal extending bars carried thereby, a plurality of transverse bars carried by pairs of said longitudinal bars angularly disposed thereon and perforated baffle plates carried by said transverse bars in front of the perforated baffle wall, the adjacent rows of said plates being angularly disposed in opposite directions and staggered relatively to each other. 20

In witness whereof I have hereunto set my hand.

ALBERT EDMUND HUDSON.
